MEANS FOR CASTING LARGE ACCUMULATOR PLATES

Filed July 9, 1929

UNITED STATES PATENT OFFICE

JOHN ALFRED FULLILOVE, OF MARKET HARBOROUGH, ENGLAND

MEANS FOR CASTING LARGE ACCUMULATOR PLATES

Application filed July 9, 1929, Serial No. 377,005, and in Great Britain July 23, 1928.

This invention relates to an improved method of and means for die casting large Plante accumulator plates where the exposed surfaces require to be split up or deeply ribbed.

The invention comprises a particular construction of the mould the essential feature of which is that the mould is built up of a number of separately movable sections each of which consists of separate mould elements for instance of steel separated one from the other by other plates, forming distance pieces these distance pieces being so disposed that they do not extend into the mould, the mould elements alone forming the mould surfaces. These mould elements are thus a number of blades separated by spaces one from the other and take the same form as though the mould was of the usual solid form with the surface milled to give the desired ribbing to the casting.

The mould is built up as aforesaid of a number of separate mould parts or sections adapted to fit the frame work of the mould and these parts are according to my invention provided with lugs or bridges which co-operate with eccentrics or other such devices so that they can be withdrawn from the casting after it has been made by mechanism located outside the mould.

The mould as a whole will of course, consist of two main parts adapted to be brought together into operative relation so that the metal injected edgewise through a nozzle will pass between the two parts and form a casting each surface of which will be formed by the mould parts aforesaid. One of these main parts can be withdrawn from the casting in sections by the operation of the eccentric device alluded to which will leave the cast plate with one of its ribbed surfaces free and the other still connected to the other mould part. The mould can then be operated and the casting can either be stripped from the other mould part or the other mould part may

be withdrawn in sections in similar manner to that before indicated and the result will be a completely cast plate having both its surfaces suitably ribbed.

In the accompanying drawings I have illustrated an example of my invention, Figure 1 being a full view of one of the mould parts, Figure 2 is a vertical longitudinal section through the mould into the parts in position ready for casting, Figure 3 is an end view and part section on the line A—A of Figure 2, and Figure 4 is a perspective view of one of the mould sections of which, in the example shown four are employed—two in each part of the mould.

It is to be understood that for larger sizes of plates further of these mould sections are used and in practice I have employed as many as eighteen—nine in each half of the mould.

Referring to these drawings throughout which, like numerals of reference indicate corresponding parts throughout the numeral 1 designates a mould section each of which is built up of a number of plates 2 preferably of steel divided as at 3 at their operative or inner edges to give the desired ribbed formation to the surface of the cast plate. These plates 2 are separated one from the other by distance plates 4 which may be of brass and the whole are held together by means of through bolts 5 riveted over at their ends and the block of plates 2 and 4 are carried upon a block 6 to which they may be united in any suitable way, as for instance, by a dovetail fitment 7.

These mould sections fit in recesses in the mould block 8 in the abutting faces of which the channels 9 for the plate frames or borders and the terminal lugs are provided. The mould blocks are slidably mounted in a fixed frame 10 and an orifice 11 is provided in the lower wall of this fixed frame 10 to enable the casting metal to be injected to the nozzle passage 12 and thence into the mould between the abutting mould sections.

In operation the two mould blocks 8 are brought together into abutment and the opposing mould sections 1 are closed up to their casting positions as shown clearly in Figure 2. This moving of the mould sections into and out of position can be effected by any suitable mechanism and in the example shown eccentrics 13, mounted on spindles 14 carried in brackets 15, mounted on each side 10 of the backs of the mould blocks 8, are employed. These eccentrics co-operate with bridges 16 carried on the back of the mould sections and it will be seen that if the eccentrics are rotated in one direction, by means of 15 the handle 17 the mould sections will be forced into casting position, as shown, which, after the casting has been effected, rotation of the eccentrics in the reverse direction will withdraw the sections from the cast plate so 20 that when the mould blocks 8 are moved away from each other the cast plate can be readily removed. The arrangement can be such that the mould sections 1 can be withdrawn separately or they can be withdrawn 25 in groups but, in any event, it will be seen that they are necessarily withdrawn as independent sections and this has proved of primary importance. In fact, it is only by reason of this splitting up of the plate into sections 30 that the larger plates can be cast. It will be understood that the molten lead, of which the plates are made, is injected through the orifice 11 and the nozzle passage 12 under pressure and the usual air outlet 35 provided so that the metal flows without obstruction throughout the mould. It will also be understood that when casting large sized plates the metal may be injected at more than one position.

40 The foregoing invention renders it possible to cast quite large Plante plates—such as are required for house lighting accumulators—in a machine. The important feature of the invention being the construction 45 of the mould sections and the provision of a mould made up of sections so that although all the sections may be withdrawn simultaneously the sections are each supported and guided in a permanent frame and each operate 50 as separate units of comparatively small area.

What I claim and desire to secure by Letters Patent is:—

1. A mould for casting large accumulator plates, comprising oppositely disposed sides, means for holding the sides in position to form a mould, a plurality of movable sections and means for moving the sections outwardly relatively to the mould, each of the oppositely disposed sides comprising a number of the movable sections, and the movable means of each section being independent so that any section can be removed from the casting independently of the others.
2. A mould for casting large accumulator

plates, comprising oppositely disposed sides having on their inner faces grooves and projecting ridges to form corresponding ridges and grooves on the casting, means for holding the sides in position to form a mould, means for moving the said sides away from the casting, each side being divided into sections of which the removable means are independent of those of the other sections, so that any section can be removed from the casting independently of the others and in a direction to draw the ridges thereon directly out of the grooves of the casting without injury to the casting.

3. A mould for casting large accumulator plates, comprising a frame, removable oppositely disposed sides fitting in said frame, a plurality of movable sections and means for moving the sections outward relatively to the frame, each of the oppositely disposed sides comprising a number of the movable sections, and the movable means of each section being independent so that any section can be removed from the face of the casting independently of the others.

4. A mould for casting large accumulator plates, comprising oppositely disposed sides, means for holding the sides in position to form a mould, a plurality of movable sections, a plurality of eccentrics mounted on shafts, bearings for carrying the shafts, means for rotating the shafts, means for holding the eccentrics in operative relation to the movable sections, each of the oppositely disposed sides comprising a number of the movable sections, the bearings of the shafts being fixed on the portions of the sides beyond these sections, and each section being engaged by one of the eccentrics so that by the rotation of its shaft it can be made to remove the section from the casting independently of the other sections.

5. A mold for casting large accumulator plates, comprising oppositely disposed sides, means for holding the sides in position to form a mould, a plurality of movable sections, a plurality of eccentrics mounted on shafts, bearings for carrying the shafts, means for rotating the shafts, bridges for holding the eccentrics in operative engagement with the movable sections, each of the oppositely disposed sides comprising a number of the movable sections, the bearings of the shafts being fixed on the portions of the sides beyond these sections, and the bridges being fixed on the movable sections so that by the rotation of its shaft each eccentric can be made to remove a mould section from the casting independently of the others.

6. A mould for casting large accumulator plates, comprising oppositely disposed sides, means for holding the sides in position to form a mould, a plurality of movable sections, a plurality of plates of uniform depth and a plurality of distance plates, a plurality

of plate carrying blocks, and means for moving the blocks outwardly relatively to the mould, each of the oppositely disposed sides comprising a number of the movable sections, and each section consisting of a number of the plates of uniform depth and distance plates riveted together to form a moulding surface having grooves and projecting ridges and fixed on one of the blocks, and the movable means of each block being independent so that any block can be removed away from the face of the casting independently of the others.

In witness whereof I affix my signature.

JOHN ALFRED FULLILOVE.
